UNITED STATES PATENT OFFICE.

WILLARD S. PAIN, OF MERIDEN, CONNECTICUT, ASSIGNOR TO AEOLIAN COMPANY, OF NEW YORK, N. Y., A CORPORATION OF CONNECTICUT

PERFORATED MUSIC-SHEET AND TRACKER-BOARD.

980,555.

Specification of Letters Patent.

Patented Jan 3, 1911.

Application filed May 11, 1909. Serial No. 495,240.

To all whom it may concern:

Be it known that I, WILLARD S. PAIN, a citizen of the United States, and a resident of Meriden, in the county of New Haven 5 and State of Connecticut, have invented certain new and useful Improvements in Perforated Music-Sheets and Tracker-Boards, of which the following is a specification.

This invention relates to improvements in 10 music sheets and tracker boards to be used in connection therewith and relates particularly to that class of music sheets and instruments therefor which are provided with accenting devices and with supplementary 15 ducts in the tracker board for leading to pneumatic means for operating the accenting devices. Heretofore accenting holes have been provided along the edge of the sheet so as to register with special ducts at 20 the ends of the row of ordinary ducts in the tracker board, but due to the shrinkage of the paper and other irregularities it frequently occurs that these accent holes do not properly register with the special ducts 25 in the tracker board and it also occurs that when the bearings for the rolls are shifted laterally so that the ordinary music note slots register properly with their ducts, the accent apertures are thrown out of register 30 with the supplemental ducts.

The object of my invention is to avoid these difficulties in a simple and effective manner.

In the accompanying drawings in which 35 like letters of reference indicate like parts in all the figures:—Figure 1 is a face view of my improved music sheet, parts being broken away and others omitted. Fig. 2 is a vertical longitudinal sectional view of 40 the tracker board, parts being broken away.

The note sheet 1 is provided with the usual note slots 2 arranged according to the melody and which are to register with the corresponding ducts 3 in the tracker board 45 4. At each end the tracker board is provided with a supplemental duct 5 which is considerably wider at its mouth than the ordinary ducts 3. I have shown such a duct 5 at each end of the tracker board as 50 the tracker board shown is to be used in an instrument which has the mechanism divided into two parts, one for the bass and one for the treble. Of course if the instrument does not have such division it will not 55 be necessary to have two ducts 5 and a single

duct will suffice. The note sheet 1 is provided along its edges with accent apertures 6 which are made small and always appear in multiple, that is in groups of at least two, but both apertures 6 of one group are 60 on the same transverse line of the sheet and are to register with one and the same duct 5. Of course it will be understood that when there is only one duct 5 in the tracker apertures 6 need be arranged only along one edge 65 of the sheet but when there is a duct 5 at each end of the tracker board the apertures 6 must be arranged along both edges of the sheet. If the sheet is displaced transversely to its length and longitudinal to the tracker 70 board, as frequently occurs in playing, this displacement does not necessarily interfere with the tracking of the note slots 2 with their ducts 3 because even if these note slots only partially track with the ducts 3 the 75 playing pneumatics will still respond. But such displacement is sufficient to bring the small accent apertures 6 out of tracking position with the ducts 5 and for this reason these small apertures 6 are made in multiple 80 as I have shown, and I prefer to make them in duplicate as a greater number might weaken the note sheet too much at the edges. These note sheets are not subject to any great stress nor are they apt to be injured any- 85 where except at the edges which must retain to as great an extent as possible, the inherent stiffness of the paper, as otherwise they are apt to be turned or folded over thus preventing proper tracking. It is therefore 90 not permissible in view of the nature of the paper to weaken the edge parts to any great extent and accent openings of the size of the smallest punch for a note slot would make holes so large that the edge of the 95 paper would be weakened to such an extent that it would not only be apt to be doubled over but would be torn. Extended tests of my improved note sheets as described above have shown that the multiple small openings 100 in transverse rows in the sheet do not weaken the edge of the sheet and do not cause the same to be turned or doubled over.

Having described my invention what I claim as new and desire to secure by Letters 105 Patent is:—

The combination with a tracker board, for pneumatic key instrument player, which tracker board has a supplemental duct in addition to the usual note ducts, the dimen- 110

sions of the mouth of which, in the direction of the length of the tracker, are considerably greater than the dimensions of the note ducts in the direction of the length of the tracker, of a music sheet having accent apertures in multiple in line transversely to the length of the sheet and located between the edge of the sheet and the space reserved for the note slots, the dimension of said apertures in the direction transversely to the length of the sheet being minute and con-

siderably less than the corresponding dimension of the note slots, substantially as set forth.

Signed at Meriden in the county of New Haven and State of Connecticut this 5th day of May A. D. 1909.

WILLARD S. PAIN.
